US00D647956S

(12) **United States Design Patent**
Kweon et al.

(10) **Patent No.:** **US D647,956 S**
(45) **Date of Patent:** **** Nov. 1, 2011**

(54) **DEVELOPING DEVICE FOR A LASER
PRINTER**

(75) Inventors: **Dae-Seob Kweon**, Kyunggi-do (KR);
Jong-In Kim, Kyunggi-do (KR);
Sang-Hoon Lee, Kyunggi-do (KR)

(73) Assignee: **Samsung Electronics Co., Ltd.**,
Kyunggi-do (KR)

(**) Term: **14 Years**

(21) Appl. No.: **29/348,991**

(22) Filed: **Feb. 26, 2010**

(51) LOC (9) Cl. **16-03**

(52) U.S. Cl. **D18/43**

(58) Field of Classification Search D14/471;

(57) **CLAIM**

The ornamental design for a developing device for a laser printer, as shown and described.

DESCRIPTION

FIG. 1 is a top front perspective view of a developing device for a laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
